DESIGN FOR AN ELECTRIC HAND LAMP

Mason M. Warner, Chicago, Ill.

Application March 17, 1944, Serial No. 112,941

Term of patent 14 years

(Cl. D48—24)

To all whom it may concern:

Be it known that I, Mason M. Warner, a citizen of the United States, residing at Chicago, in the county of Cook and State of Illinois, have invented a new, original, and ornamental Design for an Electric Hand Lamp, of which the following in a specification, reference being had to the accompanying drawing, forming a part thereof.

The figure is a perspective view of an electric hand lamp, showing my new design.

The side and rear of the lamp not appearing in the drawing are plain.

I claim:

The ornamental design for an electric hand lamp, as shown and described.

MASON M. WARNER.
